ANGLE AND DISTANCE GAUGE

Robert L. Ebinger and Cecil E. Meree,
Charleston, S. C.

Application January 23, 1943, Serial No. 473,366

7 Claims. (Cl. 33—174)

This invention relates to angle and distance gauges and is useful in measuring the angle and distance between two separated surfaces.

The invention consists broadly of two parallel bars secured together by adjustable locking means which will permit adjustment of the angle and the distance of separation between the two bars. Normally the two bars are held apart by suitable biasing springs, but when the bars are set at a desired angle they may be locked in that position until released.

An object of the invention is to devise an angle and distance gauge which is symmetrical in its operation, that is, it may be employed for measuring either divergent or convergent angles from either end of the gauge.

A further object is to devise a gauge of the type described having adjustable locking means provided at each end of the gauge and a common operating member for the two locking means positioned to be accessible at one end of the gauge.

A preferred embodiment of the invention is illustrated in the accompanying drawing in which

Figure 1 is a side elevational view of the gauge shown in working position for measuring the size of a liner to be inserted between the base of a machine and the floor on which the machine is to be supported;

Figure 2 is a plan view of the gauge;

Figure 3 is an enlarged sectional view of the gauge taken along the line 3—3 of Figure 1;

Figure 4 is an enlarged sectional view taken along the line 4—4 of Figure 1;

Figure 5 is an enlarged sectional view taken along the line 5—5 of Figure 2; and

Figure 6 is a perspective view of a wedge embodied in the locking means.

Referring to the drawing, the two parallel bars are shown at 1a and 1b. These bars are preferably formed of metal, such as steel, but they may be formed of any suitable material. As shown in Figure 1, the bars 1a and 1b are tapered in opposite directions in a complementary manner so that the wide end of one bar is adjacent the narrow end of the other bar. The two bars are normally urged apart by means of a pair of biasing springs 2a and 2b, the ends of which are seated in sockets or bores formed in the opposing faces of bars 1a and 1b. A pair of link elements 3a and 3b are provided at the ends of the gauge and serve to limit the amount of separation of the two bars by springs 2a and 2b. One end of the link 3a is positioned in a slot formed

in bar 1b and is pivotally secured to the bar by means of a pin 4a. In a like manner one end of link 3b is positioned in a slot formed in bar 1a and is pivotally secured to this bar by pin 4b. The free ends of links 3a and 3b extend into slots formed in bars 1a and 1b, respectively. Link 3a is slideably secured to bar 1a by a pin 5a which passes through a longitudinal slot formed in link 3a. As more clearly shown in Figure 3, pin 5a is provided with a head 5a' which is loosely positioned in a bore formed in one side wall of bar 1a and is seated against link 3a. The pin 5a extends through the bar and projects beyond the opposite face of the bar as shown in Figure 3. In a like manner, link 3b extends into a slot formed in the wide end of bar 1b and is adjustably secured to bar 1b by means of a pin 5b having a head 5b'.

Pins 5a and 5b are provided with longitudinal slots formed therein for receiving wedges 6a and 6b which slide along the opposite side of bars 1a and 1b from the heads of pins 5a and 5b and serve to draw the pins forward and clamp links 3a and 3b to bars 1a and 1b. Wedges 6a and 6b are provided with bosses 6a' and 6b' at the thick ends thereof by which the wedges may be operated simultaneously by suitable means to clamp or release the links 3a and 3b.

One suitable arrangement for operating the two clamping wedges is shown in the drawing and consists of a rod or shaft 7 journaled in a bearing formed in boss 6b' and having threaded engagement at one end with the boss 6a'. A collar 1a is fixed on shaft 7 and is positioned in a transverse slot formed in boss 6b'. The shaft 7 may be rotated by means of a knob 7b positioned adjacent one end of the gauge, although it is obvious that the shaft 7 may be extended beyond the other end of the gauge and an operating knob provided at each end of the shaft. Rotation of shaft 7 in one direction will cause the two wedges 6a and 6b to approach each other and clamp the links 3a and 3b to bars 1a and 1b, respectively, and rotation of shaft 7 in the opposite direction will release the two clamps. A pair of stop pins 8a and 8b are secured to the sides of bars 1a and 1b in positions to prevent withdrawal of the wedges 6a and 6b from the slots in pins 5a and 5b and to prevent unscrewing of the boss 6a' from shaft 7. It will be understood that with the arrangement shown, each wedge serves to supply the reaction force necessary to clamp or release the other wedge. For example, if wedge 6a releases first, then this wedge moves to the left until it engages stop pin

8a and then wedge 6a supplies the necessary reaction for releasing wedge 6b. In a similar manner, if wedge 6a should have the greater resistance to being released, wedge 6b will release first and then move to the right with shaft 7 until it engages stop pin 8b and will then supply the necessary reaction to release wedge 6a.

It will be noted that the operating force for operating the two clamping devices is applied directly between the two movable elements of the clamping devices, whereby each clamping device serves as a reaction element for the other clamping device. This arrangement insures the simultaneous operation of the two clamping devices and reduces the possibility of one clamping device being tightly clamped when the other is not entirely clamped.

It will also be noted that the clamping forces applied by wedges 6a and 6b to clamp the spacer links 3a and 3b to the bars 1a and 1b are applied in a direction transversely of the common plane of the parallel bars. This arrangement serves to clamp the bars in position without imposing any unnecessary strain or force on the pivots 4a and 4b, and there is no tendency of these clamping forces to disturb the relative positions of the two bars.

Suitable distance graduations are formed on the side face of each bar at the outer edge thereof such as the inch graduations shown on the side face of bar 1b in Figure 1.

One manner of using the gauge is shown in Figure 1 where the gauge is inserted between the base B of a machine which is to be mounted on a sloping floor F, and it is desired to determine the size of the liner which is to be inserted between the base and the floor in order to support the machine in a level position. The locking shaft is first released so that the two bars are urged outwardly to the full extent of their movement by springs 2a and 2b. The two bars are then pressed together by hand and inserted beneath the base B and the gauge is moved under the base until one edge of the base comes opposite some convenient graduation on bar 1b. Due to the action of springs 2a and 2b, the two bars will be urged against the floor and the lower face of the base, respectively, and will automatically assume the correct angular position for the two faces of the liner. The locking shaft 7 is now rotated to clamp the two bars in the fixed angular relation, and before removing the gauge from beneath the base, a note is made of the reading on the graduation on bar 1b at the right edge of base B which will indicate the width of the liner. The gauge may now be removed and the angle between the outer faces of the two bars will indicate the correct angle for the opposing faces of the liner to be inserted beneath the base of the machine. The angle measured in Figure 1 is convergent from the right end of the gauge but it is obvious that the gauge will also measure divergent angles as well. In other words, the gauge may be used to measure angles sloping in either direction from either end within the limits permitted by links 3a and 3b. It is also obvious that the gauge is not limited in its use to measuring the angle between inclined separated surfaces, but it may also be used to measure the distance between the two parallel separated surfaces.

For the purpose of increasing the operating range of the gauge, a supplemental height bar may be added to one of the two parallel bars. For example, in the right end of Figure 1 we

have shown a fragmentary part of a supplemental height bar 1c positioned on the upper face of bar 1b. These supplemental bars may be removably secured to the main bar by any suitable means such as dowel pins 1c'. A set of these bars may be provided for each gauge, the bars being of different heights to provide different ranges of operation.

It will be understood that the construction illustrated and described herein is the preferred embodiment but the invention is not limited to the exact construction shown, since it will be obvious that the construction may be varied in various details without departing from the spirit of the invention. One obvious modification would be to provide threaded engagement between the shaft 7 and boss 6b', instead of using the connection by means of the collar 7a, but this threaded connection would have a pitch opposite to the threaded connection with boss 6a', so that the two bosses would move in opposite directions when the shaft 7 is rotated. Other modifications will be obvious to those skilled in the art.

25. What we claim is:

1. A gauge comprising a pair of parallel bars, a pair of adjustable clamping devices mounted at spaced points along said bars for adjustably clamping said bars in fixed spaced relation, a 30 rotary shaft carried by said gauge and mounted substantially parallel with said bars, said rotary shaft having threaded engagement with the movable operating element of one of said clamping devices so that rotation of said shaft moves said 35 operating element towards or away from the other clamping device.

2. A gauge comprising a pair of parallel bars, a pair of adjustable clamping devices mounted at spaced points along said bars for adjustably clamping said bars in fixed spaced relation, a common operating member for said clamping devices, and connections from said common operating member to said clamping devices for applying an operating force directly between said 45 clamping devices so that each clamping device serves as a reaction element for the other clamping device, whereby the clamping pressures of said clamping devices are substantially equalized.

3. A gauge according to claim 2 wherein the 50 operating element of each clamping device comprises a movable wedge, the two wedges facing in opposite directions, and the common operating member for said clamping devices serves to move said wedges in opposite directions.

55. 4. A gauge comprising a pair of parallel bars, two spacer links arranged transversely of said bars near the ends thereof, means for pivotally connecting one end of each spacer link to one 60 of said bars on an axis transversely of the plane of said bars, separate devices for clamping the free end of each of said spacer links to the adjacent bar by a clamping force applied transversely of the plane of said bars, and a common operating member for said separate clamping 65 devices comprising a rotary shaft mounted parallel with said bars and being connected for operating said clamping devices so that one device serves as a reaction element for the other clamping device, whereby the clamping pressures of said clamping devices are substantially equalized.

70. 5. A gauge comprising a pair of parallel bars, said bars being tapered in a complementary manner whereby the narrow end of one bar lies adjacent the wide end of the other bar, a spacer link pivotally connected at one end to the nar-

row end of one bar, a second spacer link pivotally connected at one end to the narrow end of the other bar, each of said spacer links extending transversely of the pivotally connected bars and extending into slots formed in the wide ends of the adjacent bars, a clamping device carried by the wide end of each of said bars and embodying means for clamping the free end of the spacer link against the side wall of the slot formed in the associated bar, and a common operating member for said clamping devices and having an operating handle positioned at one end of said gauge.

6. A gauge according to claim 5 wherein each of said clamping devices includes a wedge for pressing the spacer link into engagement with a side wall of the surrounding slot, said wedges being directed in opposite directions, and said common operating member comprising a rotary shaft

having threaded connection with one wedge and a rotary connection to the other wedge whereby the operating force of one wedge is applied as a reaction force to the other wedge.

5 7. A gauge comprising a pair of parallel bars, a pair of adjustable clamping devices mounted at spaced points along said bars for adjustably clamping said bars in fixed spaced relation, a rotary shaft carried by said gauge and mounted substantially parallel with said bars, said rotary shaft having threaded engagement with the movable operating element of one clamping device, and a connection from said shaft to the other clamping device to transmit the reaction force from said threaded connection to the movable operating element of the second clamping device.
